UNITED STATES PATENT OFFICE

CHARLES A. TURNER, OF CHICAGO, ILLINOIS, ASSIGNOR TO UNIVERSAL ELECTRIC CONTROLLER COMPANY, OF CHICAGO, ILLINOIS, A CORPORATION OF ILLINOIS

SIGNAL AND RECORDING DEVICE

Application filed December 14, 1927. Serial No. 239,939.

My present invention relates to the provision of signal and recording devices for use in connection with supervisory and alarm circuits and has particular relation to the provision of such instrumentalities in connection with a main supervisory location.

As will hereafter be seen I have provided means whereby when an alarm circuit is closed in the general supervisory and alarm circuit, my instrument will display a target disclosing that the alarm of the general supervisory circuit has functioned and it will also make a record to the same effect. In addition to the displaying of the target and the making of the record it will be seen that local signals, preferably auditory and visual, will be energized until the apparatus is restored to set position, and that the mechanism cannot be restored to eliminate the local signal until 20 the alarm circuit in the general supervisory circuit is opened or cleared.

I have attained the foregoing objects and results by means of the structure illustrated in the accompanying drawing in which—

25 Fig. 1 is a schematic detail partially in section of the divers elements of my invention excepting the target shown in elevation and in operative relation.

Fig. 2 is a section on line 2—2 of Fig. 1, the 30 portions above this line being removed for clearness.

Fig. 3 is a perspective of the rocker shaft and the instrumentalities attached thereto.

Fig. 4 is a schematic diagram of the circuit 35 involved in the operation of the present instrumentalities and its relation to the alarm circuit of a general supervisory and alarm organization; and

Fig. 5 is a schematic end view of the movable, and stationary targets.

Similar reference characters have been employed to designate similar parts throughout the respective views.

45 My device is preferably installed in a cabinet which has normally displayed a stationary target 10 as shown in Fig. 5, on which are inscriptions designating that the apparatus is in normal condition. Back of the target 10 is journaled a shaft 11 adjacent the ends of which are secured disks, 11^a, having periph-

eral flanges 11^b from which extend radially arms 12 upon the ends of which is a target 13 adapted when the shaft 11 is rotated to fall in front of the target 10, and on this target 13 should be placed indicia indicating that the 55 circuit is functioning to give an alarm and requires attention. The shaft 11 is yieldingly maintained so as to hold the target 13 in elevated position by a suitable spring 11^c attached at one end to a stationary pin and 60 at the other to the disc 11^a. Mounted on the shaft 11 is a grooved pulley 14 to which is secured and about which wraps, when the target 13 is in elevated position, a ball or other suitable chain 15, which passes over a 65 pulley 16 and descends into a tube 18 in the lower end of which it is secured by a split washer 19 of about the diameter of the tube 18 and of sufficient diameter to prevent its being drawn therein.

70 About the tube 18 is swetted or otherwise suitably secured a collar 20 of sufficient thickness to form the lower abutment or stop for a coiled expansion spring 21. The tube 18, collar 20 and spring 21 are mounted in an exterior tube 22 with a flanged top at 23 serving as the top abutment of the expansion spring 21 and a flanged bottom 24 serving as a stop for the collar 20. Pinned to the portion of the lower end of the tube 18 which 75 extends below the tube 22 is an annular head or collar 25. This collar 25 is flanged laterally at the top, as at 26, and its side below the top is slightly angled away from the axis of these parts for a purpose to be hereafter 80 described.

Pivoted in a base plate 27 disposed at right angles to and below the above described parts, is a plate 28 to the top of which is pivoted or hinged at 29 an upper plate 30. The top of the plate 30 abuts the flange 26 of the head 25 and the angle of the vertical portion of the head 25 is such that the lower pivotal connection of the plate 28 and the hinge 29 are sufficiently on or near center to support the head 25 and tube 18 in elevated position against the downward thrust of the spring 21. The angling of the side of the head 25 is for the purpose of determining the direction 95 in which the plates 28 and 30 will fold to- 100

gether and also to make their support of the head 25 sensitive to a capsizing influence.

Located parallel with and adjacent to the tubes 23 and 18 is a hollow solenoid 31 into which extends a headed plunger 32. Adjacent the bottom of the plunger 32 and at right angles thereto is a rocker shaft 33 one end whereof is split, as at 34, to receive a curved plate 35, the unattached end of which is bored, as at 36, for the passage of the stem of the headed plunger 32.

As will be seen, when current flows in the solenoid 31 the plunger 32 will be retracted and the head thereof will strike the plate 35 which will rock the rocker shaft 33. Fixed in and extending from the rocker shaft is a trigger 37 which is disposed, as shown in Fig. 1, to kick the hinge 29 and throw the bearing points of the plates 28 and 30 off center and permit the spring 21 to expand and the tube 18 and its head 25 to be forced downwardly.

Located on the opposite side of the plates 28 and 30 to the rocker shaft 33 is a plunger 38, which is mounted to reciprocate in two spaced blocks 39 and 40, which are preferably made of insulating material and are secured to the base plate 27. A block 41 is pinned, or otherwise suitably and fixedly secured to the plunger 38 between the blocks 39 and 40 and a coiled spring 42 is interposed between the blocks 39 and 41 to press the plunger 38 away from the plates 28 and 30.

Secured to an end of the rocker shaft 33 is a latch plate 43 provided in its outer unsecured under side with a recess 44 adapted to fall over and engage a pin 45 extending from an end of the block 41, when the plunger 38 is adjacent but not in contact with the plate 28.

The plunger 38 has as one of its functions, the restoring of plates 28 and 30 to their supporting position with relation to the head 25 which is accomplished by pressing inwardly the portion of the plunger extending beyond the block 40 until the plates 28 and 30 are in proper supporting position, but upon the manual release of the end of the plunger 38 it travels but a short distance from the plate 28 before it is caught by the latching arm 43. The latching arm 43 is arranged with relation to the rocker shaft 33 so as to slightly lead the movement of the trigger 37 so that the plunger 38 is mechanically released to the action of the spring 42 before it is struck by the descending head 25 through the plate 28.

Pivoted on the end of block 39 is stylus arm 46 which carries on its end and at right angles thereto a stylus tube 47 in the end of which is an awl or stylus 48. In the end 60 of the moving block 41 opposite to that in which is carried the pin 45 is a pin 49 upon the top of which rests the bottom of stylus arm 46, which is cut away to provide the detent 50 and flat portions 51 and 52 on opposite sides of the detent, the travel of which

flat portions over the pin 49 imparts no movement to the stylus arm, while the travel of the detent 50 over the pin 49 in either direction will force the stylus arm upwardly so as to puncture a tape 53 carried adjacent the stylus on suitable rollers 54.

Mounted upon the top of the block 39 and extending in the direction of the block 40 and insulated from each other are a lower, an intermediate and an upper contact blades 55, 56 and 57, respectively, the end of the intermediate blade 56 being extended beyond the other blades and formed to provide a downwardly extending projection 56a, which is engaged and forced upwardly so as to establish contact between the middle and upper blades by a pin 58 carried in the top of block 41. The intermediate blade is flexed slightly downwardly so that when it is relieved from the support of pin 58 it will break contact with the upper contact blade 57 and establish contact with the lower contact blade 55.

As has been previously explained this signal and recording apparatus is designed for use in connection with a general electrical supervisory and alarm system. All that it is necessary to know at this time with respect to the general electrical supervisory and alarm system is that it comprises, among other features, a general alarm circuit, shown in Fig. 4, by the parallelly disposed conductors *a* and *b*, between which are bridged various signaling devices *c*, such as lamps and sound producers. When this circuit is closed the elements *c* will be energized. Preferably from the high side, hot, or positive conductor *a*, of the general alarm circuit, I run the conductor *d* to the central switch blade 56 and from the top switch blade 57 I run the conductor *e* to the top of the solenoid 31, from the bottom of which solenoid conductor *f* runs to the low, minus, neutral, or ground side *b* of the general alarm circuit.

It will be seen that when the general alarm circuit is energized the solenoid 31 will also be energized, the plunger 32 retracted, the plate 35 engaged, the rocker shaft 33 rotated and trigger 37 and latch bar 43 operated to release plunger 38 and tube 18 with its head 25.

In order to provide further audible and oral local signals to indicate that the apparatus should be restored, I run a conductor *g* from the high side of the general source of electrical supply, which feeds through a lamp *h* and a buzzer *k* arranged in parallel to a conductor *l* which leads to the bottom contact blade 55. The lamp and buzzer *h* and *k* are chosen so that they will be operated by and will pass a current of less energy than is requisite in operating the devices *c* in the general alarm circuit *a b*. It will now be seen that when the pin 58 carried by the block 41 has moved from under the central contact blade 56 and permitted it to fall into contact

with the lower blade 55, the local alarm elements *h* and *k* will be energized and will continue to operate until the devices are restored to initial position.

5 It will also be seen that this restoration cannot be accomplished until the general alarm circuit has been cleared because if this circuit had not been cleared the solenoid 31 would again be energized and the sequence 10 of activities heretofore described would again occur.

Having described my invention what I claim as new and desire to secure by Letters Patent is:

15 1. A signal and recording device comprising a spring pressed plunger, a pivoted element for holding said plunger in retracted position, a rocker shaft, an element carried thereby for releasing said holding means from said plunger, a second plunger for restoring said spring pressed plunger and holding means to mitral relation, a latch for said restorer plunger carried by said rocker, a recording arm actuated by said restorer 20 plunger, a solenoid, a movable plunger therefore, a plate carried by said rocker arm extending into co-active relation with the plunger of said solenoid and a switch operated by said restorer plunger to open the circuit of said solenoid when the same is in unlatched position.

25 2. A signal and recording device comprising a pivoted stylus carrying arm, a restorer plunger and means carried thereby for actuating said arm, a double pivoted link support, a spring pressed plunger held in retracted position by said support, a trigger for capsizing said support, a latch for holding said restorer plunger in impressed position, a rocker arm to which said trigger and latch 30 are secured, a plate carried by said rocker arm, a solenoid and a plunger operated by said solenoid for engaging said plate.

35 3. A signal and recording device comprising a spring pressed plunger, capsizable means for supporting said plunger in a retracted position, means for restoring said capsizable means to supporting position, recording means operable by said restorer, a 40 rocker arm, means for capsizing said capsizable means and means for latching said restorer carried by said rocker shaft, a solenoid and a plunger operated thereby, and means carried by said rocker arm and extending into 45 co-active relation with said last mentioned plunger.

4. A signal and recording device comprising a spring pressed plunger, capsizable means for supporting said plunger in a retracted position, means for restoring said capsizable means to supporting position, recording means operable by said restorer, a rocker arm, means for capsizing said capsizable means and means for latching said restorer carried by said rocker shaft, a solenoid

and a plunger operated thereby, means carried by said rocker arm and extending into co-active relation with said last mentioned plunger and a three bladed switch operated by the movement of said restorer to close contact alternately between the center and the exterior blades. 70

5. In a signal and recording device comprising recording means and restorer means, a spring pressed plunger and supporting means, a motor comprising a spring pressed plunger, means for holding said motor in retracted position comprising a plurality of pivoted links which fold or collapse when said pivots are off center. 75

6. A signal and recording device comprising a spring actuated motor member, a collapsible element for holding said motor member in set position, a restorer, recording means, electrical means for capsizing said collapsible element, local alarm element, and means operated by the restorer for alternately closing the circuits of said electrical elements. 80

7. In a signal and recording device a spring 90 actuated motor element, a capsizable element for holding said motor element in set position, electrical means for capsizing said collapsible element, a fixed target, a target pivoted to rotate in front of said fixed target, 95 and means operable by said motor element for causing such rotation.

8. In a signal and recording device a latched motor element, electrical means for unlatching said motor element, a circuit including said last mentioned means, and a local alarm circuit, and means actuated by the mechanical movement of said device to open one and close the other of said circuits. 100

9. In a signal and recording device a reciprocating spring actuated motor element, collapsible means for maintaining said motor element in set position, electrically operated means for capsizing said collapsible element, and means for restoring said motor element 110 and collapsible element to set position. 105

10. In a signal and recording device a reciprocating spring actuated motor element, collapsible means for maintaining said motor element in set position, electrically operated means for capsizing said collapsible element, and means for restoring said motor element 115 and collapsible element to set position and simultaneously closing the circuit of said electrical element. 120

CHARLES A. TURNER.
